(57) **CLAIM**

The ornamental design for a skid mounted light tower with generator, as shown and described.

DESCRIPTION

FIG. 1 is a front view of the embodiment of the skid mounted light tower with generator;

FIG. 2 is a rear view of the embodiment of the skid mounted light tower with generator of the embodiment of FIG. 1; FIG. 3 is a right view of the embodiment of the skid mounted light tower with generator of the embodiment of FIG. 1; FIG. 4 is a left view of the embodiment of the skid mounted light tower with generator of the embodiment of FIG. 1; FIG. 5 is a top view of the embodiment of the skid mounted light tower with generator of the embodiment of FIG. 1; FIG. 6 is a bottom view of the embodiment of the skid mounted light tower with generator of the embodiment of FIG. 1; FIG. 7 is a perspective view of the embodiment of the skid mounted light tower with generator of the embodiment of FIG. 1; FIG. 8 is another perspective view of the embodiment of the skid mounted light tower with generator of the embodiment of FIG. 1; FIG. 9 is another perspective view of the embodiment of the skid mounted light tower with generator of the embodiment of FIG. 1; and FIG. 10 is a front view of the embodiment of the skid mounted light tower with generator; FIG. 11 is a rear view of the embodiment of the skid mounted light tower with generator of the embodiment of FIG. 1; FIG. 12 is a right view of the embodiment of the skid mounted light tower with generator of the embodiment of FIG. 1; FIG. 13 is a left view of the embodiment of the skid mounted light tower with generator of the embodiment of FIG. 1; FIG. 14 is a top view of the embodiment of the skid mounted light tower with generator of the embodiment of FIG. 1; FIG. 15 is a bottom view of the embodiment of the skid mounted light tower with generator of the embodiment of FIG. 1; FIG. 16 is a perspective view of the embodiment of the skid mounted light tower with generator of the embodiment of FIG. 1; and FIG. 17 is another perspective view of the embodiment of the skid mounted light tower with generator of the embodiment of FIG. 1.

(Continued)

FIGS. 1 to 9 show the skid mounted light tower with generator in a retracted position. FIGS. 10 to 17 show the skid mounted light tower with generator in an extended position.
